UNITED STATES PATENT OFFICE.

HERBERT WILSON, OF TOLEDO, OHIO, ASSIGNOR TO THE DURA COMPANY, OF TOLEDO, OHIO, A CORPORATION OF DELAWARE.

DESIGN FOR A GUIDE PLATE FOR A WINDOW STRAP, DOOR LOCK LEVER, OR SIMILAR ARTICLE OF MANUFACTURE.

Application filed January 28, 1924. Serial No. 8,447. Term of patent 7 years.

To all whom it may concern:

Be it known that I, HERBERT WILSON, a citizen of the United States of America, residing at Toledo, in the county of Lucas and State of Ohio, have invented a new, original, and ornamental Design for a Guide Plate for a Window Strap, Door Lock Lever, or Similar Article of Manufacture, of which the following is a specification, reference being had therein to the accompanying drawings, forming part thereof, in which—

Fig. 1 is a plan view of a guide plate for a window strap, door lock lever, or similar article of manufacture, showing my new design; Fig. 2 is a side elevation thereof; and Fig. 3 is an end elevation thereof.

I claim:

The ornamental design for a guide plate for a window strap, door lock lever, or similar article of manufacture, substantially as shown.

HERBERT WILSON.
